Primary Examiner — Kevin Rudzinski*(74) Attorney, Agent, or Firm* — Greenberg Traurig LLP**CLAIM**

We claim the ornamental design for a fan light cover, as shown and described.

DESCRIPTION

FIG. 1 is a perspective view of a fan light cover;
 FIG. 2 is a top view of the fan light cover shown in FIG. 1; and,
 FIG. 3 is a side view of the fan light cover shown in FIG. 1.
 The present application is directed to the shape and contour of
 the design illustrated in the drawings. The broken line show-
 ing of the environment is for illustrative purposes only and
 forms no part of the claimed design.
